US00D917461S

(12) **United States Design Patent** (10) **Patent No.:** **US D917,461 S**
(45) **Date of Patent:** **** Apr. 27, 2021**

(54) **PORTABLE INFORMATION HANDLING SYSTEM**

(71) Applicant: **Dell Products L.P.**, Round Rock, TX (US)

(72) Inventors: **Nicholas Gregory DiLoreto**, Austin, TX (US); **Duck Soo Choi**, Austin, TX (US)

(73) Assignee: **Dell Products L.P.**, Round Rock, TX (US)

(**) Term: **15 Years**

(21) Appl. No.: **29/669,207**

(22) Filed: **Nov. 6, 2018**

(51) LOC (13) Cl. **14-02**

(52) U.S. Cl.

USPC **D14/327**

(58) **Field of Classification Search**

(57) **CLAIM**

The ornamental design for a portable information handling system, as shown and described.

DESCRIPTION

FIG. 1 is a front perspective view of the portable information handling system in a closed configuration comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the portable information handling system shown in an open configuration; and, FIG. 9 is a top perspective view of the portable information handling system shown in another open configuration.

Broken lines shown in the drawings illustrate portions of the portable information handling system and form no part of the claimed design.

1 Claim, 7 Drawing Sheets
